Primary Examiner — Mary Ann Calabrese(74) *Attorney, Agent, or Firm* — Schmeiser, Olsen & Watts LLP; Timothy P. Collins(57) **CLAIM**

An ornamental design for a self-checkout station, as shown and described.

DESCRIPTION

FIG. 1 is a front perspective view of a self-checkout station; FIG. 2 is a rear perspective view of the self-checkout station of FIG. 1;

FIG. 3 is a right side view of the self-checkout station of FIG. 1;

FIG. 4 is a left side view of the self-checkout station of FIG. 1;

FIG. 5 is a front view of the self-checkout station of FIGS. 1-4;

FIG. 6 is a rear view of the self-checkout station of FIGS. 1-5;

FIG. 7 is a top view of the self-checkout station of FIGS. 1-6; and,

FIG. 8 is a bottom view of the self-checkout station of FIGS. 1-7.

In the drawings, the broken lines illustrate portions of the self-checkout station which form no part of the claimed design.
